SUPPLYING SUPERHEATED STEAM TO
LOCOMOTIVE ENGINE CYLINDERSEugene L. Schellens, Ridgewood, N. J., assignor to
C-S Engineering Company, Englewood, N. J.,
a corporation of Delaware

Application June 2, 1937, Serial No. 145,921

9 Claims. (Cl. 122—462)

This invention relates to locomotives and to apparatus for superheating the steam and for conducting the superheated steam to the engine cylinders.

5 One of the objects of the present invention is the provision of a superheater unit adapted to be positioned within a fire tube or gas flue of the locomotive boiler and so constructed and arranged as to have high heating efficiency and low steam 10 resistance and also to offer low resistance to the flow of combustion gases through the fire tube.

The usual type of superheater unit comprises a plurality of return-bend tubes through the long passes of which the steam flows in series and 15 in opposite directions and alternately counter to and with the flow of gases in the fire tube. In such a superheater unit the tube passes wherein the steam flows in the direction of flow of gas are relatively inefficient in transferring heat to 20 the steam from the combustion gases as compared with the heat transfer in the counter-flow passes of the superheater unit. Such a superheater unit also has a relatively high drop in steam pressure between its inlet and outlet ends.

25 Hence a further object of the invention is an improved form of superheater unit having a relatively large number of tube passes in which the steam flows counter to the flow of gas and a small number of tube passes, and preferably one tube 30 pass of large diameter in which the steam flows with the flow of gas so that the unit has high thermal efficiency and also large steam area whereby the drop in pressure between the inlet and outlet of the unit is low.

35 A further object of the invention is the provision of a superheater unit consisting of a plurality of small tubes connected in parallel to a common manifold and surrounding a large return tube to which the small tubes are connected at 40 the ends remote from the manifold, the large return tube passing through the manifold and being free from rigid connection therewith so as to permit relative expansion and contraction movement 45 between the small tubes and the return tube.

45 In the superheater embodying the present invention there is provided a saturated steam header having a plurality of depending branch headers. There is also provided a superheated steam header having a plurality of branch headers. In 50 accordance with the present invention the superheated steam headers and the saturated steam headers are tapered in opposite directions and are free from rigid interconnections and a vertical group of superheater units are connected with a 55 saturated and a superheated steam header in

such a way that the same freedom for expansion and contraction movement toward and away from the front tube sheet of the boiler is permitted at any one of the superheater units. Such a construction constitutes a further object of the invention.

Another object of the invention is the provision of superheated and saturated steam branch headers that are arranged one behind the other in line with a vertical bank of fire tubes and the 10 superheater units therein, the superheater unit having a saturated steam manifold provided with an entrance tube which is disposed sufficiently at one side of the saturated steam header so that it can be connected therewith with but a single 15 bend, the superheated steam outlet of the unit being in axial line with the superheated steam branch header so that it can be connected with the branch header by a tube having but one bend 20 therein.

In the usual superheater construction the superheater units are connected with the saturated and superheated steam headers through a large number of connections that by reason of space 25 limitations cannot be secured together sufficiently strongly to surely prevent steam leakage and as a consequence one of the objections to this type of superheater is the leakage of steam into the smoke box and the resultant clogging of the 30 smoke box screening.

It is an object of the present invention to provide a superheater construction wherein the superheater units are connected to the headers through but a relatively small number of joints 35 which are spaced apart sufficiently to permit the use of clamping flanges and bolts of ample size.

Another object of the invention is the provision of a superheater unit comprising a series of tubes operating in parallel and connected to a common return tube through a connection of novel 40 construction.

Another object of the invention is the provision of a header construction and particularly a superheater header construction comprising a 45 plurality of tubes welded or otherwise secured to the smoke box shell and upstanding therein and receiving branch headers at their upper ends and opening at their lower ends into a main header that is disposed on the outside of the smoke box shell.

The main superheater header is disposed transversely of the smoke box shell and at its opposite ends is provided with throttle valves and separate steam connections from the throttle valves to the locomotive cylinders. This arrangement 55

places the throttle valves desirably close to the cylinders and permits the use of a separate throttle valve for each cylinder and constitutes a further object of the invention.

5 Another object of the invention is the provision of improved operating mechanism for the throttle valves so arranged that they are caused to be opened by approximately the same amounts and to be surely closed, the operating mechanism 10 including equalizing mechanism that is interposed between the valves and the throttle lever in the locomotive cab, the mechanism being disposed beneath the locomotive boiler. While it has been proposed heretofore to provide a locomotive with a throttle valve for each of its two cylinders, the valves being located outside of the locomotive shell in separate pipes that passed into the shell, the operating mechanism for the valves necessarily was constrained to pass 15 through the smoke box where it was liable to become fouled and rendered inoperative by the cinders and dust therein. This objection is obviated by the present construction.

A further object is generally to improve the 25 construction and operation of devices for superheating the steam and for conducting the superheated steam to the cylinders of a locomotive.

Fig. 1 is a side elevation of a locomotive embodying the present invention and illustrating 30 particularly the individual throttle valve and steam connections between the superheated steam header and the engine cylinder.

Fig. 2 is a sectional view taken along line 2—2 of Fig. 1 and illustrating particularly a front 35 elevation of the front tube sheet and superheater headers of the locomotive.

Fig. 13 is a side elevation of the equalizing mechanism.

60 Fig. 14 is a section taken along line 14—14 of Fig. 13.

As shown especially in Fig. 3 the locomotive comprises a boiler having the boiler shell 16, the smoke box shell 18 and the front tube sheet 20. 65 A plurality of large fire tubes 22 extend rearwardly from the front tube sheet 20 and are adapted to receive superheater units. A plurality of smaller fire tubes 24 are also extended rearwardly from the front tube sheet. Saturated 70 steam passes through the dry pipe 26 into the neck 28 of a saturated steam header 30 which is disposed transversely of the smoke box shell in front of the tube sheet 20 and above the fire tubes 22. While the saturated steam header 30 75 can be of any suitable construction it preferably

is a fabricated construction consisting of a steel tube 32, the ends of which are closed by plugs 34 welded thereto, the tube being welded to the cast inlet neck 28 and having a plurality of apertured bosses 36 opening into the interior of the 5 tube welded to the under side and extended in the line of the tube 32 and providing for a plurality of branch headers 38.

The branch headers are provided at their upper ends with attaching flanges 40 through which 10 clamping bolts 42 are passed and are screw-threaded into the bosses 36. A seating disc or washer 44 is clamped between the flat face of the flange 40 and a conical seat of a boss 36 to insure a steam tight joint therebetween. The joint 15 between the branch header 38 and the main header can be depended upon to maintain itself steam tight by reason of the large bolts 42 which the construction permits.

The branch header 38 tapers in a progressive 20 manner from a large diameter at the upper end to a small diameter at the lower end thereof, the taper being for the purpose not only of providing accommodation for the different volumes of steam in different parts of the header but also 25 to render the header flexible to permit lateral bending thereof. The large fire tubes 22 are disposed in vertical lines and the branch headers 38 are disposed in front of and in line with the different vertical groups of the fire tubes. 30

The superheated branch steam headers 46 are similar in construction to the saturated steam branch headers 38 and are disposed behind said headers and in line with the vertical groups of fire tubes, the two sets of branch headers being 35 close to each other but free from any interconnection that would tend to hinder the free lateral deflection of the headers due to heating and expansion of the superheater units connected therewith. The branch headers 46 are connected through flanges 48 and 50 and the interposed sealing washers 52 and bolts 54 with the upper ends of vertical tubes 56, the lower ends of which are located in openings of the smoke box shell 18 and are secured as welded thereto. 45 The tubes 56 are of different lengths and have their upper ends in the same horizontal plane. A superheated steam header 58, generally U-shaped in cross-section and open at its upper 50 end, is welded or otherwise secured in a steam-tight manner to the outer face of the smoke box tube 18 about the openings of the tubes 56 and receives the superheated steam discharged from said tubes.

The superheated steam header 58 extends 55 transversely of and under the smoke box shell 18 and at its opposite ends is provided with steam take-off ears 60, in each of which a throttle valve is located. The construction of a take-off ear is illustrated more particularly in Fig. 60 10. As shown in this figure the parallel opposite side walls 62 of the header have coaxial openings in one of which a coupling member 64 is seated and is secured thereto by bolts 66 and in the other of which a cylinder member 68 is seated and is secured thereto by bolts 70. A pipe 72 connects each coupling member with adjacent locomotive cylinders, as is illustrated in Fig. 1. 65

A throttle valve seat member 74 is carried by the coupling member and cooperates with a throttle valve 76. Said throttle valve has a hollow stem 78 that at its other end carries a piston 80 reciprocable in the cylinder member 68. A valve rod 82 passes through the valve stem 78 and axially slotted bushings 84 therein and co- 75

operates with the piston 80 to support the throttle valve for movements toward and away from its seat. The valve stem 82 is loosely guided for longitudinal movement in the hub 86 of the valve seat member 74. The valve stem 82 is provided with a pilot valve 88 adapted to open and close the passage 90 through the valve stem 78. The valve stem is also provided with an abutment 92 which is engageable with the throttle valve 10 to move it away from its seat.

The chamber 94 of the cylinder member 68 is pressure tight and the piston 80 has a small amount of leakage between its opposite ends from the interior of the superheated steam header into the chamber 94 either by reason of the clearance between the piston 80 and the cylinder member or by reason of a leakage passage 96 through the piston. The throttle valve 76 is slightly larger in diameter than the piston 80 so that the steam pressure acting thereon in the superheated steam header tends to bias the valve for movement into closed position. When the valve is closed the chamber 94 is under the pressure of steam in the superheated steam header and hence the valve is maintained positively closed. Movement of the pilot valve 88 away from its seat on the piston 80 serves to relieve the pressure in the chamber 94 so that the throttle valve can be opened readily when the valve stem 82 has been moved sufficiently to bring the abutment 92 against the throttle valve.

The throttle valve is operated by a shaft 98 which passes through a packing gland 100 into the chamber 94 and has an arm 102 fixed thereto and extended thereabove and pivotally connected with a pair of links 104 that are pivotally connected to the valve stem 82.

The throttle valves in the opposite ends of the superheated steam header are interconnected for conjoint operation through equalizing mechanism illustrated in Figs. 2, 12, 13 and 14. The two operating shafts 98 for the two throttles are extended parallel with the superheater header and transversely under the locomotive boiler and in axial alignment and are terminated in hubs 106 and 107 which are journaled in a supporting bracket 110 secured by suitable means 112, Fig. 1, to the under side of the locomotive boiler shell. The two hubs are provided with closely confronting annular flanges 114 and 116. The flange 114 has a plurality of outstanding pins 118 which are passed loosely through openings 120 in the flange 116, the openings being sufficiently greater in diameter than the diameter of the pins to permit sufficient relative axial movement between the valve operating shafts 98 to insure the positive closing of both valves irrespective of small play between the shafts and the valves or differences in the settings of the valves.

The operating shafts 98 have equalizing arms 122 and 124 fixed thereto and extending in the same direction and terminated in pins 126 passed loosely through an equalizing bar 128 having a cylindrical mid portion 130 on which a bushing 132 is journaled. A yoke 134 has a pair of arms 136 which embrace the bushing 132 and are provided with pins 138 that are journaled in the bushing and thereby provide a universal connection between the yoke and the equalizing bar. The other end of the yoke is pivoted at 140 to the end of an arm 142 fixed to a short shaft 144 journaled in the bracket 110 and having an arm 146 fixed thereto which is adapted for con-

nection through linkage 148, see Fig. 1, with the throttle lever 150 in the engine cab.

The arrangement is such that a pull or a thrust on the equalizing bar through the yoke 134 effects the rotation of one shaft until the clearance between the pin 118 and the side wall of the opening in which it is located is taken up and then effects the rotation of both shafts with the consequent movements of both throttle valves. When, however, the valves are moved into closed position the setting of one valve upon its seat causes the equalizing bar to fulcrum upon the arm 122 or 124 associated with that valve to cause the movement of the other valve against its seat. Hence with this construction herein provided both throttle valves are caused to be surely seated.

With the throttle valve arrangement herein shown the connections between the superheated steam header and the engine cylinders are short and direct and entirely outside the smoke box 20 and the throttle valve operating mechanism is not exposed to smoke box conditions that would tend to render it inoperative.

The present construction represents a saving of several hundred pounds of weight over the usual construction wherein a pair of steam pipes run from the top of the smoke box through the shell thereof to the engine cylinders. This saving in weight is highly important in the design of locomotives that otherwise are up to their limit of weight as the weight saved by the present construction can be used advantageously to thicken the boiler shell and use increased steam pressure, for instance, thereby to render the locomotive more powerful and efficient.

The saturated and superheated steam headers are connected by a plurality of superheater units contained within the large fire tubes 22. The units are more or less identical in construction. Each unit comprises an annular spaced cluster 40 of small parallel tubes 152 surrounding and radially spaced from a large return tube 154, see Figs. 2 through 8. The small tubes 152 receive saturated steam from a generally cylindrical casting or manifold 156 located close in front of the front tube sheet and having a conical front wall 158 which confronts the open ends of the fire tubes and serves to deflect away from the manifold dust and cinders that pass through the fire tube and might otherwise lodge on the manifold. The front ends of the small tubes 152 are located in openings in the conical front wall of the manifold and are welded or otherwise secured in a steam tight manner therein. The manifold 156 is provided with a centrally located tube 160 which passes through the front conical wall 158 and also the radial back wall 162 and is welded to both walls in a steam tight manner. The return tube 154 passes loosely through said tube 160 and hence the tube and the manifold are free for relative axial movements to permit expansion and contraction of the tubes of the unit.

The inner end of the return tube 154 is closed by a plug 164 and forwardly of the plug is provided with four equiangularly spaced slots 166. Hollow ears 168 are welded to the tube 154 over the slots 166 so that the slots communicate with the chambers in the ears. Said ears 168 at the ends and opposite sides thereof are provided with side openings 170; and lateral hollow ears 172 are welded to the ears 168 about said openings. A small tube 152 is welded or otherwise secured to each of the lateral ears 172 so that all of the small tubes discharge in parallel into the inner end of 75

the common return tube 154. This described arrangement permits a ready assembly of the unit and provides for a relatively free gas flow around and lengthwise of the various tubes. The forward ends of the various ears 168 and 172 are curved or stream-lined to facilitate the flow of gas about them.

The projecting forward ends 154a of the return tubes 154 of the tube units are disposed in line with a superheated steam branch header 46 and are bent downwardly as is indicated in Fig. 3, and are welded or otherwise secured to the branch header, the downward bend of the tubes being for the purpose of facilitating the entrance of the superheated steam into the entrance of the superheated steam header. By having the large return tubes in the line of the header the connection therewith can be made by but a single bend.

20 The saturated steam manifolds 156 are provided with ears 174 which are extended all in the same direction and project beyond the lines of the sets of branch headers. Each ear is provided with an opening into which a saturated steam inlet tube 176 is secured, the pipe lying at one side of the branch header with which it is associated and being provided with a single and upward bend where it is joined with the branch header, the projecting ears 174 obviating the necessity for complicated double bends in the inlet tube that would be necessary otherwise.

All of the superheater units of a vertical row of fire tubes 22 are permanently connected to their associated pair of saturated and superheated steam branch headers and are adapted to be removed as a unit with the branch headers upon the removal of the bolts 42 and 54 which connect the branch headers with their respective main headers. The pairs of saturated and superheated steam branch headers are free from rigid interconnections and hence can flex laterally to accommodate the expansion and contraction of the tubes of the superheater units. By having the branch headers tapered, and tapered in opposite directions, the conjoint lateral deflection of the pair of headers is the same anywhere along the length of the headers and is designed to be sufficient to accommodate the maximum change in length of the tubes of the unit under the normal operating conditions.

I claim:

1. In a locomotive in combination with its boiler shell, steam superheating apparatus including a plurality of separate tubes secured to and carried by and upstanding from the interior of said shell and opening through said shell, superheater units connected with said tubes within said shell, and a superheated steam header independent of said tubes carried transversely by said shell externally thereof and encompassing the tube openings through the shell.

2. Superheater apparatus for locomotives comprising an upper saturated steam header located within and transversely of the locomotive shell and having a plurality of saturated steam outlets disposed in line at the bottom part of the header, a lower superheated steam header extended transversely of the locomotive shell including means providing a plurality of superheated steam inlets arranged in line transversely of the boiler shell and at one side of the line of said saturated steam outlets, vertical branch headers having means detachably securing them to said inlets and outlets, said branch headers being arranged in pairs and extended in opposite directions from

their associated main headers and each being integral and tapered from end to end and being free from rigid interconnection with each other except at their interconnections with their respective main headers, and a plurality of superheater units disposed in vertical lines having inlet tubes welded to a common saturated steam branch header, and outlet tubes welded to a common superheated steam branch header, said inlet and outlet tubes being free for relative expansion movement and the branch headers connected to any one superheater unit being capable of lateral flexure of different amounts in the line of such unit to accommodate such movement.

3. Superheater apparatus for locomotives comprising an upper saturated steam header located within and transversely of the locomotive shell and having a plurality of saturated steam outlets disposed in line transversely of the shell at the bottom part of the header, a lower superheated steam header extended transversely of the locomotive shell including means providing a plurality of superheated steam inlets arranged in line transversely of the boiler shell and at one side of the line of said saturated steam outlets, vertical branch headers having means detachably securing them to said inlets and outlets, said branch headers being arranged in pairs and extended in opposite directions from their associated main headers and each being integral and tapered from end to end and being free from rigid interconnection with each other except at their interconnections with their respective main headers, a plurality of superheater units disposed in vertical line having inlet tubes welded to a common saturated steam branch header, and outlet tubes welded to a common superheated steam branch header, said inlet and outlet tubes being free for relative expansion movement and said branch headers being independently capable of lateral flexure to accommodate such movement, the associated saturated and superheated steam branch headers being arranged in line with the associated superheater units and one branch header behind and spaced from the other branch header.

4. In a superheater apparatus for locomotives, the combination of removable superheated and saturated steam branch headers and a superheater unit connected therewith, said headers being arranged in the axial line of said superheater unit and one header behind and spaced from the other header, said superheater unit having an outlet tube which is in the axial line of the superheater unit and headers and is welded to the nearest header, said unit also having an inlet tube which is at one side of and parallel with the axis of the unit and passes by the near header and has an end part which is curved upwardly and is welded to the side of the remote header opposite the near header.

5. In superheater apparatus for locomotives, a saturated steam header, a superheated steam header, a superheater unit, said headers being arranged in the axial line of said unit and one header behind the other, the superheater header being nearest the superheater unit, said superheater unit including a manifold, a plurality of superheater tubes connected with said manifold, said manifold having a steam inlet located at one side of the line of said headers and a steam inlet tube connected with said inlet and passing beside said superheated steam header and having an end part curved upwardly and welded to said

saturated steam header on the side opposite said superheater branch header, said superheater unit having a common superheated steam return tube connected with the aforesaid superheater tubes 5 and disposed in the line of said superheated steam header and having a welded connection therewith.

6. A superheater unit for locomotives adapted for insertion in a fire tube thereof including a common return tube, an annular saturated steam manifold having a sliding connection with said tube at the outer end thereof and having a front wall and a conically shaped rear wall that confronts the end of the fire tube, and a plurality 10 of superheater tubes surrounding and extended lengthwise of said return tube and having connections with the interior of said manifold through said conical wall and having connections with the inner end of said return tube, said manifold having a steam inlet through its outer wall.

7. A superheater unit for locomotives including an annular series of superheater tubes, a common return tube disposed within said series of superheater tubes, said return tube at one end 25 having a plurality of outstanding circumferentially spaced hollow ears opening into the interior of said return tube, the ears being located between and each communicating with a pair of said superheater tubes, and the tubes opening into the sides of said ears.

8. A superheater unit for locomotives including an annular series of generally parallel superheater tubes, a common return tube for said 30 superheater tube disposed within said annular series, said tube having a plurality of outstand-

ing circumferentially spaced hollow ears opening into the interior of said tube, each of said ears having oppositely laterally projecting ears, and a pair of superheater tubes connected with said last named laterally projecting ears.

9. Superheater apparatus for locomotives comprising upper and lower saturated and superheated steam main headers, the upper saturated steam header having a plurality of downwardly-facing saturated steam outlets, and the lower 10 superheated steam header having a plurality of upwardly facing superheated steam inlets, individual vertical saturated steam branch headers having means detachably securing them to said outlets and extended downwardly from said saturated steam main header, individual superheated steam branch headers having means detachably securing them to said inlets and extended upwardly from said superheated steam main header, 15 each of said branch headers being integral and tapered from one end to the other and being free from rigid interconnections with each other except through their connections with the main headers, and a vertical group of superheater units 20 having inlet tubes welded to a common saturated steam branch header and outlet tubes welded to a common superheated steam branch header, said inlet and outlet tubes being free for relative expansion movement and the branch headers 25 connected to any one superheater unit being capable of lateral flexure of different amounts in the line of such unit to accommodate such movement.

EUGENE L. SCHELLENS.
